UNITED STATES PATENT OFFICE.

VALENTINE LEHNERD, OF WEST HOBOKEN, NEW JERSEY, ASSIGNOR TO FR. PUSTET & CO., OF NEW YORK, N. Y.

DESIGN FOR A BADGE.

SPECIFICATION forming part of Design No. 33,906, dated January 15, 1901.

Application filed December 20, 1900. Serial No. 40,591. Term of patent 14 years.

To all whom it may concern:

Be it known that I, VALENTINE LEHNERD, a citizen of the United States, residing at West Hoboken, Hudson county, New Jersey, have 5 invented and produced a new and original Design for Badges, of which the following is a specification, reference being had to the accompanying drawing, which shows a face view of the same.

- 10 The leading or material features of my design are a portion having a heart-shaped configuration and a portion surmounting the same and being of a clover-leaf configuration or three-lobed.
- 15 A indicates the heart-shaped portion, and B the three-lobed portion, the bases of both joining each other.

Within the heart-shaped portion A is a heart-shaped figure C, and surmounting the latter and located in the clover-leaf portion B 20 is a figure D in the form of a Greek cross.

What I claim is—

The design for a badge, substantially as shown and described.

In testimony that I claim the foregoing as 25 my invention I have signed my name in presence of two subscribing witnesses.

VALENTINE LEHNERD.
